Term of patent 7 years

(Cl. D9—2)

Fig. 1

Fig. 2

Fig. 3

FIGURE 1 is a perspective view of a vacuum cleaner, showing my new design;

FIGURE 2 is an enlarged fragmentary view thereof;

FIGURE 3 is a top plan view thereof, the broken line portion being omitted for convenience of illustration.

The side not shown is substantially like the side shown. The tube and cord are shown broken away in FIGURE 1 for convenience of illustration.

The dominant features of my design reside in the portions shown in full lines.

I claim:

The ornamental design for a vacuum cleaner, as shown and described.
